UNITED STATES PATENT OFFICE.

ALEXANDER BOEHM, OF NEW YORK, N. Y., ASSIGNOR TO LOUIS LEVI AND
ALEXANDER MAYER, BOTH OF SAME PLACE.

REVERSIBLE RUCHING FOR LADIES' NECK-WEAR.

SPECIFICATION forming part of Letters Patent No. 349,297, dated September 21, 1886.

Application filed November 25, 1884. Renewed October 29, 1885. Serial No. 181,315. (No model.)

To all whom it may concern:

Be it known that I, ALEXANDER BOEHM, of the city, county, and State of New York, have invented an Improvement in Ladies' Neck-Wear, of which the following is a full, clear, and exact description, reference being had to the accompanying drawings.

The object of my invention is to provide certain new and useful improvements in neck-wear, whereby a better fit of the same is obtained and it is rendered less apt to become detached, loosened, or displaced.

The invention consists in ladies' neck-wear—such as ruching—provided with a pliable metal spring stiffener concealed within the band of such ruching, which retains the shape given to the article of neck-wear and renders it reversible.

In the accompanying drawings, Figure 1 is a perspective view of a piece of my improved ladies' neck-wear, parts being broken out. Fig. 2 is a cross-sectional view of the same.

Like letters of reference indicate like parts.

The neck-wear A, made of ruching, lace, or any other material usually used for making such articles, is formed with a bottom band or strip, B, to which the ruching or other material is secured, the said band or strip being

hollow. In the said hollow strip or band I conceal a pliable spring, C, made of metal. 30

The neck-wear can be bent in any desired shape and to bring either side out, and will always form handsome curves, and will fit well against the neck and in the neck-opening of the dress. It need not be pinned or otherwise fastened at the back, and need only be held in front by the usual breastpin, it is not easily displaced, and retains its shape perfectly, whereby the neck-wear is made more durable. 35

I do not claim a collar having a stiffening-spring of definite length attached to the collar-band. 40

My invention is applicable to ruchings and the like of indefinite length.

The ruching can be cut into pieces of desired 45 length, the spring being cut at the same time, and the ruching can then be put around a wrist or neck and afterward reversed, if desired.

I claim—

The reversible ruching having concealed 50 within its band B the pliable metal spring C, substantially as herein shown and described.

ALEXANDER BOEHM.
